United States Patent Office

Des. 189,690
Patented Jan. 31, 1961

189,690

STOCKING

Richard B. Sheek, Winston-Salem, N.C., assignor to Hanes Hosiery Mills Company, Winston-Salem, N.C., a corporation of North Carolina

Filed Feb. 23, 1960, Ser. No. 59,470

Term of patent 14 years

(Cl. D47—7)

FIG. 1 —

FIG. 2 -

Fig. 1 is a schematic side view of a stocking showing my new design; and

Fig. 2 is a fragmentary view of the stocking as it appears against a black background.

The opposite side of the stocking has the same appearance as that shown in the drawings.

I claim:

The ornamental design for a stocking, as shown and described.
